(57) **CLAIM**

The ornamental design for semi-octopost extrusion, as shown and described.

DESCRIPTION

FIG. 1 is a top, left front perspective view of semi-octopost extrusion showing my new design;
FIG. 2 is a front elevational view thereof;
FIG. 3 is a top plan view thereof;
FIG. 4 is a bottom plan view thereof;
FIG. 5 is a right side view thereof; and,
FIG. 6 is a left side elevational view thereof.
